COMBINED FURNITURE REST AND WALL GUARD

Roger Edouard Guillaumant, Valparaiso, Ind.

Application October 8, 1954, Serial No. 32,600

Term of patent 14 years

(Cl. D10—6)

The broken line portion of the drawing is for illustrative purposes only.

I claim:

The ornamental design for a combined furniture rest and wall guard, as shown, and described.
